(57) **CLAIM**

The ornamental design for a glasses strap, as shown and described.

DESCRIPTION

FIG. 1 is a perspective view of a glasses strap showing my new design;

FIG. 2 is a front view thereof;

FIG. 3 is a rear view thereof;

FIG. 4 is a top view thereof; and,

FIG. 5 is a bottom view thereof.

The broken lines in FIGS. 1-5 depict portions of the glasses strap that form no part of the claimed design.
